UNITED STATES PATENT OFFICE.

CLARE BROWN, OF DETROIT, MICHIGAN.

CARRIER.

Application filed January 24, 1925. Serial No. 4,585.

This invention relates to carriers of the aerial or suspended type and has for an object the provision of a carrier by means of which material may be transported, deposited and the carrier returned to its former or loading position with the aid of a single operator, the invention being especially adapted for moving manure from a stable or barn to a desired location.

More specifically stated, the invention provides a carrier which may be loaded and its operation manually started, whereupon the carrier will travel with its load to a predetermined point, will automatically dump its load and automatically reverse its direction of travel so that it will be returned to its original position without requiring the services of an operator to travel with the carrier or to be stationed at its point of unloading.

With the above and other objects in view, the invention further includes the following novel features and details of construction, to be hereinafter more fully described, illustrated in the accompanying drawings and pointed out in the appended claims.

In the drawings:—

Figure 1 is a side elevation of the invention.

Figure 2 is an end view showing the track in section.

Figure 3 is an enlarged fragmentary sectional view taken substantially on the line 3—3 of Figure 1.

Figure 4 is an enlarged fragmentary longitudinal section illustrating the controlling clutch.

Figure 5 is a fragmentary view illustrating the reversing switch of the motor.

Figure 6 is a sectional view showing the ratchet for controlling the direction of rotation of the operation shaft.

Figure 7 is a diagrammatic view illustrating the wiring.

Referring to the drawings in detail wherein like characters of reference denote corresponding parts, the reference character 10 indicates the rails of a track which may be supported in any suitable manner, such as

by hangers 11. This track supports a carriage which includes a frame 12 and grooved traction wheels 13, the latter operating over the rails 10.

Mounted within suitable bearings provided in the carriage or frame 12 is an operating shaft 14. This shaft extends longi-

tudinally of the carriage and has mounted for free rotation and longitudinal sliding movement thereon a gear 15. The gear 15 is engaged and driven by a gear 16, the latter being mounted upon the shaft of a motor 17. The motor is suitably supported upon the frame 12 of the carriage and receives current from the rails 10 through collector brushes 18. These brushes are included in circuit with the motor 17 by means of conductor wires 19, the latter being connected to a reversing switch 20 which is provided with an operating handle 21. This handle is adapted to be engaged to move the switch so that the latter will engage spaced contact pins 21 and 22 to rotate the motor in one direction, or contact pins 22 and 23 to rotate the motor in an opposite direction. A manually operated switch 24 is included in the motor circuit so that the motor may receive current from a suitable source indicated at 25.

Secured upon the shaft 14 is a sleeve 26 and carried by this sleeve is a gear 27 which engages a gear 28, the latter being secured upon a shaft 29 which is rotatable in suitable bearings provided in the frame 12. The gear 28 engages a gear 30 and this last mentioned gear is secured to one of the shafts 31 upon which the grooved traction wheels 13 are mounted. The end of the sleeve 26 opposite the gear 27 is provided with a clutch face 32 which is adapted to engage the adjacent face of a clutch member 33 which extends from one side of the gear 30. The opposite side of the gear 15 has extending therefrom a clutch face 34 which is adapted to engage a clutch member 35 fast upon the shaft 14. Thus, when the clutch members 32 and 33 are engaged and the motor operated, power will be supplied to the traction wheels 13 so as to move the carriage along the track.

Mounted upon the shaft 14 are drums 36 and wound upon these drums are the upper ends of chains or cables 37. The lower ends of these chains or cables are secured as indicated at 38 to the opposite ends of a receptacle 39, the point of connection between the chains and receptacle being slightly to one side of its vertical center so that the receptacle may readily tilt in one direction. Tilting in this direction however is prevented by means of stop lugs 40 which are secured to the opposite ends of the container and which engage the chains 37.

Operatively associated with the slid-able

members 33 and 34 of the clutch as indicated at 41 is a clutch arm or lever 42. This arm is longitudinally slotted as indicated at 43 and receives a pivot pin 44 which is carried by a cam disk 45. This disk is provided with a pin 46 which extends from one face upon opposite sides of the clutch arm 42, the pins being adapted to engage the arm when the disk 45 is rotated. Rigid with the disk is a substantially L-shaped arm 49 whose outer extremity is provided with a right angularly disposed portion 50 which is located in the path of upward movement of the receptacle 39. Extending from the periphery of the disk 45 is an offset or cam portion 51 having a notch 52 therein. The walls of this notch are engaged by a spring actuated plunger 53 which is mounted for movement upon the frame 12.

Pivottally mounted upon the frame 12 as indicated at 54 is an angle lever 59. One arm of this lever extends horizontally inward and is adapted to be engaged by a stop 56 which is secured to one rail 12 of the track. The vertically disposed arm of the angle lever 59 extends downward and is adapted to be moved to engage the receptacle 39 for a purpose to be later explained. The stop 56 is also located in the path of the operating handle 21 of the reversing switch 20.

Secured upon the shaft 14 is a ratchet wheel 60 which is adapted to be engaged by a spring actuated dog 61 carried by the frame of the carriage.

In the operation of the invention, the receptacle is lowered by manually moving the clutch members 33 and 34 to a neutral position, illustrated in Figure 4 of the drawings, and by disengaging the dog 61 from the ratchet wheel 60 so as to permit of the rotation of the shaft 14 and consequent unwinding of the chains 37. The clutch is then manually operated to engage the clutch members 34 and 35, in which position the spring actuated plunger 53 will engage the notch 52 in the cam disk 45. When current is applied to the motor 17 through closing the switch 24, the shaft 14 will be rotated to wind the chains 37 upon the drums 36 and raise the receptacle 39. As the right angled portion 50 of the lever 49 is disposed in the path of upward movement of the receptacle 39, the lever 49 will be swung pivotally upward as shown by the dotted lines in Figure 1. The plunger 53 will yield and be disengaged from the notch 52 whereupon one of the beveled faces of the plunger will engage the upper inclined face of the cam extension 50 and will act to quickly rotate the cam so as to cause the clutch members 32 and 33 to engage. Motion will thus be imparted to the traction wheels 13 through the gearing previously

described so that the carrier will move along the track. As soon as the horizontal arm of the angle lever 59 engages the stop 56, the vertical arm of this lever will be moved pivotally inward to engage the side of the receptacle 39, the latter being in the position illustrated by the dotted lines in Figure 2. This will overbalance the receptacle and cause the latter to tilt and dump its load. Immediately following the dumping operation, the operating handle 21 of the reversing switch 20 will engage the stop 56 so as to throw the switch and cause the latter to engage the contacts 22 and 23. The polarity of the motor will thus be reversed and the carriage will reverse its direction of travel. When the carriage reaches the loading point its travel may be stopped by opening the switch 24.

The invention is susceptible of various changes in its form, proportions and minor details of construction and the right is herein reserved to make such changes as properly fall within the scope of the appended claims.

Having described the invention what is claimed is:—

1. A carrier comprising a receptacle, a carriage, a track supporting the carriage, a motor, a shaft supported by the carriage, flexible means connecting the receptacle and shaft, a clutch member fast upon the shaft, carriage operating mechanism, a clutch member rotatable upon the shaft and operatively associated with the carriage operating mechanism, a clutch member slidable upon the shaft between the fast clutch member and the rotatable clutch member and operatively associated with the motor, means to control the operation of the motor to control the operation of the shaft and elevate the receptacle when the slidable clutch member is engaged with the fast clutch member, means to hold said members in engaged position and means located in the path of upward movement of the receptacle to release the holding means and cause engagement between the slidable clutch member and the rotatable clutch member to operate the carriage.

2. A carrier comprising a receptacle, a carriage, a track supporting the carriage, a motor, a shaft supported by the carriage, flexible means connecting the receptacle and shaft, a clutch member fast upon the shaft, carriage operating mechanism, a clutch member rotatable upon the shaft and operatively associated with the carriage operating mechanism, a clutch member slidable upon the shaft between the fast clutch member and the rotatable clutch member and operatively associated with the motor, means to control the operation of the motor to control the operation of the shaft and elevate the receptacle when the slidable

- clutch member is engaged with the fast clutch member, a pivotally mounted cam operatively associated with the slidable clutch member to control the latter, yieldable means to hold the cam against movement, means associated with the cam and located in the path of upward movement of the receptacle to operate said cam and disengage the slid-
10 member and means included in the cam and acted upon by the yieldable holding means to cause the slidable clutch member to engage the rotatable clutch member and operate the carriage.
- 15 3. A carrier comprising a receptacle, a carriage, a track supporting the carriage, a motor, a shaft supported by the carriage, flexible means connecting the receptacle and shaft, a clutch member fast upon the shaft, carriage operating mechanism, a clutch member rotatable upon the shaft and op-
20 eratively associated with the carriage operating mechanism, a clutch member slid-
25 able upon the shaft between the fast clutch member and the rotatable clutch member and operatively associated with the motor, means to control the operation of the motor to control the operation of the shaft and elevate the receptacle when the slidable clutch member is engaged with the fast clutch member, a pivotally mounted cam operatively as-
30 sociated with the slidable clutch member and having its periphery provided with a recess and a cam surface adjacent said recess, a spring actuated plunger engageable within the recess to yieldingly hold the slidable clutch member engaged with the fast clutch member and means rigid with the cam and located in the path of upward movement of the receptacle to move the cam pivotally to disengage the plunger from the recess and disengage the slidable clutch from the fast clutch member, whereby, the cam will be positioned to cause the spring actuated plunger to engage the cam at one side of the recess and move the slidable cam mem-
35 ber into engagement with the rotatable cam member.
- 40 the cam and acted upon by the spring actu-
ated plunger to cause the slidable clutch member to engage the rotatable clutch member and operate the carriage.
4. A carrier comprising a receptacle, a carriage, a track supporting the carriage, a motor, a shaft supported by the carriage, flexible means connecting the receptacle and shaft, a clutch member fast upon the shaft, carriage operating mechanism, a clutch member rotatable upon the shaft and op-
45 eratively associated with the carriage operating mechanism, a clutch member slid-
50 able upon the shaft between the fast clutch member and the rotatable clutch member and operatively associated with the motor, means to control the operation of the motor to control the operation of the shaft and elevate the receptacle when the slidable clutch member is engaged with the fast clutch member, a pivotally mounted cam operatively as-
55 sociated with the slidable clutch member and having its periphery provided with a recess and a cam surface adjacent said recess, a spring actuated plunger engageable within the recess to yieldingly hold the slidable clutch member engaged with the fast clutch member and means rigid with the cam and located in the path of upward movement of the receptacle to move the cam pivotally to disengage the plunger from the recess and disengage the slidable clutch from the fast clutch member, whereby, the cam will be positioned to cause the spring actuated plunger to engage the cam at one side of the recess and move the slidable cam mem-
60 ber into engagement with the rotatable cam member.
- 65 In testimony whereof I affix my signature.
